GAS BURNER HEAD AND SECONDARY
AIR BAFFLE

Marc Resek, Cleveland Heights, Ohio, assignor to
Perfection Stove Company, Cleveland, Ohio, a
corporation of Ohio

Application October 6, 1949, Serial No. 119,975

2 Claims. (Cl. 158—116)

1

This invention relates to gas burners, particularly of the type used extensively, though not necessarily exclusively, in cooking stoves and ranges.

It is the fundamental object of my invention to produce a gas burner of the aforesaid type that efficiently consumes more gas in a given time, and, accordingly, affords a greater heat output, than prior burners of similar type and comparable size.

More specifically stated, my principal purpose is to provide a gas burner having a maximum gas emitting port area, as by increasing, relative to prevailing practice, the number of ports, or the size thereof, or both, and incorporating in the burner means for delivering to each port the requisite amount of air to render combustion of the gas issuing therefrom substantially complete.

In the form of my invention presently preferred, the burner comprises a hollow annular head that encloses a gas chamber and surrounds a central vertical air passage or flue. The head is provided with gas emitting ports about its periphery adjacent its top, and said ports are desirably arranged in two circumferential rows that are spaced apart a suitable distance in a vertical direction, the ports of one row being out of vertical alignment with those of the other row. Means, desirably in the form of a Y-shaped mixing tube or so-called venturi, is provided for supplying gas to said chamber, the branches of said tube joining the bottom of the head on opposite sides of said central air passage or flue. Supported above in suitably spaced relation to the top of the burner head is a disc-like deflector, the edge of which is above the peripheral portion of the head. When the burner is in operation, this deflector serves to direct the air rising through the central passage or flue outwardly across the top of the burner and in such relation to the gas emitting ports that an ample quantity of air is supplied to the gas issuing therefrom to render combustion of the gas substantially complete. Where two vertically spaced rows of apertures are used, as in the present preferred form of the invention, air supply for the apertures of the lower row is principally supplied by the air which naturally rises about the periphery of the burner head during burner operation. However, with air supplied from both above and below, all jets of gas issuing from the apertures are insured a quantity of air ample for combustion purposes.

A further object of the invention is to so shape the aforesaid deflector that it will enhance the appearance of the burner; that it will effectively change the direction of flow of air rising through the central passage or flue from a vertical to a horizontal direction, and that, by reason of its shape, the deflector will be prevented from warping and snapping back and forth due to alternate

2

heating and cooling, such as might occur if the deflector were a flat disc.

One embodiment of my invention is shown in the accompanying drawing, and while I shall proceed to describe the same in detail, it will be understood that the invention is not thus limited, but is subject to such change and modification as may come within the scope of the claims appended hereto.

In the drawing, Fig. 1 is a side elevational view of a burner incorporating my improvements, with the lower end of the mixing tube or venturi broken away; Fig. 2 is a plan view of the burner, and Fig. 3 is an enlarged vertical section through the top portion of the burner on the line 3—3 of Fig. 2.

The burner is preferably fabricated of sheet metal, and in this respect, as well as in construction, it follows quite closely certain embodiments of an invention that forms the subject matter of the application of Harris A. Squire, et al., Serial No. 19,554, filed April 7, 1948.

In the several views of the drawing, the head of the burner is designated generally by the reference letter A, the mixing or Venturi tube by the letter B, and the deflector by the letter C.

The head A consists of an inverted sheet metal channel member a¹, and a bottom wall a². The web portion of the channel member a¹ constitutes a flat top wall a³, and the outer and inner flanges thereof provide a peripheral wall a⁴, and an inner wall a⁵, respectively. The top wall merges through rounded corners into downwardly diverging portions of the inner and outer walls, the latter wall assuming a cylindrical shape throughout its lower region. The inner wall a⁵ terminates at its lower end in an inturned flange a⁶, above which, for a short distance, said wall is cylindrical. The flange a⁶ is a considerable distance above the plane of the lower edge of the outer wall a⁴, and fitted into the lower end of the latter wall is a depending edge flange a⁷ of the bottom wall a². Inwardly of a flat annular portion a⁸ thereof, the bottom wall assumes a frusto-conical shape and terminates in a flange a⁹ that is engaged with and is welded to the previously mentioned flange a⁶ to produce a gas-tight joint. Similarly treated is the joint between the edge flange of the bottom wall a² and the adjacent edge of the outer wall a⁴. The bottom wall a² has diametrically opposite openings through which the upper ends of the branches b' of the mixing or Venturi tube B are projected, this preferably being done before the parts of the head A are joined together so that the joint between the ends of the branches and the wall a⁴ may be welded on the inside, as indicated in Fig. 3. Also prior to assembling the head A, a ring a¹⁰ is fitted into the channel a', with an annular flat portion a¹¹ of the ring engaged with the under-

side of the top wall a^3 . Extending downwardly and outwardly from the portion a^{11} of the ring a^{10} is a wall a^{12} whose lower edge is curved outwardly into contact with the wall a^4 , the major portion of the wall a^{12} being spaced from and substantially parallel to the downwardly divergent portion of the wall a^4 . The ring a^{10} is fastened to the channel member a^1 , desirably by shouldered rivets D , the reduced lower ends of said rivets being extended through registering holes in the wall a^3 and portion a^{11} of the ring a^{10} and upset inwardly of the latter, as clearly shown in Fig. 3. Gas emitting ports a^{15} are made in the walls a^4 and a^{12} , corresponding parts of the two walls preferably being axially aligned.

In a sheet metal burner construction, such as shown herein and in the beforementioned application, the above described port characteristic is desirable because the corresponding ports of the two walls provide, jointly, a port depth of proper ratio to port diameter to prevent flashback, or the withdrawal of the flame to within the burner head, especially at low burning rate.

The shouldered rivets D serve the further purpose of attaching the deflector C to the burner head and of properly spacing its edge portion from the underlying peripheral portion of the head. Holes of proper size and spacing are formed in the annular flat edge portion c^1 of the deflector, and through said holes are extended the reduced upper ends of the rivets D . The deflector is then fastened to the protruding ends of the rivets, preferably by welding. Throughout its central region, the deflector is curved or arched upwardly to provide a shallow dome-like portion c^2 . It is found that by shaping the deflector in this fashion, the current of air rising through the flue or passage surrounded by the burner head is turned laterally and horizontally for projection outwardly through the slot-like space between the straight edge portion c^1 of the deflector and the underlying flat top wall of the burner head. From the relatively large volume of air thus supplied to the region immediately above the peripheral portion of the head and that which rises about the burner head during burner operation, ample air is supplied to the jets of gas issuing from the apertures a^{15} .

Having thus described my invention, what I claim is:

1. A gas burner comprising an annular head providing a central air passage, said head being formed by two sheet metal elements, the first of said elements being of channel formation and including a top wall, a peripheral wall, and an inner wall, the second sheet metal element being formed to provide a substantially flat bottom wall having its outer edge connected to the lower edge of said peripheral wall and its inner edge joined to the lower edge of said inner wall, a sheet metal ring-like member nested in the first described element and having an annular flat portion engaged with said top wall and a downwardly divergent peripheral wall substantially parallel to the surrounding portion of the first mentioned peripheral wall and in contact therewith adjacent the lower edge of the member, said peripheral walls being provided with gas emitting ports, the top wall and underlying portion of said ring-like member having registering apertures that are spaced apart about the head, fastening means extending through said apertures and

serving to bind said member to the top wall, a deflector having a shallow dome-shaped central portion and arranged above and in substantially concentric relation to the head, said means having their upper ends connected to the deflector whereby the latter is supported above and in spaced relation to the head with its edge above the peripheral portion thereof, and means for supplying gas to the space enclosed by said sheet metal elements.

2. A gas burner comprising an annular head providing a central air passage, said head being formed by two sheet metal elements, the first of said elements being of channel formation and including a substantially flat top wall, a peripheral wall flaring downwardly therefrom a distance and then terminating in a cylindrical portion, and an inner wall that extends generally downwardly and inwardly from the top wall and terminates in an edge portion that is spaced a substantial distance above the plane of the bottom edge of said peripheral wall, the second sheet metal element being formed to provide a substantially flat bottom wall having a depending peripheral flange that fits within the lower end of said peripheral wall and is joined thereto, said bottom wall being flanged upwardly and inwardly about its inner edge and connected to the lower edge portion of the aforesaid inner wall, a sheet metal ring-like member nested in the first element and having an annular flat portion engaged with said top wall and a downwardly divergent peripheral wall substantially parallel to the surrounding portion of the first mentioned peripheral wall and in contact therewith adjacent the lower edge of the member, said peripheral walls being provided with gas emitting ports, the top wall and underlying portion of said ring-like member having registering apertures that are spaced apart about the head, fastening means having reduced lower ends extended through said apertures and provided with abutments below said underlying portion of the ring-like member to bind said member to the top wall, a circular deflector having a flat peripheral portion and a shallow dome-shaped central portion, said peripheral portion being provided with apertures, and said fastening means having reduced upper ends extended through said apertures and connected to the deflector whereby the latter is supported above and in spaced relation to the head with its edge above the peripheral portion thereof, the bottom wall having an opening, and a mixing tube having its upper end connected to the bottom wall about said opening.
